UNITED STATES PATENT OFFICE.

ANDREW B. KOENIG AND JOSEPH B. VAN CLEVE, OF ST. LOUIS, MISSOURI.

BELL ATTACHMENT FOR BANJOS OR GUITARS.

SPECIFICATION forming part of Letters Patent No. 416,064, dated November 26, 1889.

Application filed May 6, 1889. Serial No. 309,730. (No model.)

To all whom it may concern:

Be it known that we, ANDREW B. KOENIG and JOSEPH B. VAN CLEVE, both of the city of St. Louis, in the State of Missouri, have invented a certain new and useful Improvement in Bell Attachments for Banjos, Guitars, or Similar Instruments, of which the following is a full, clear, and exact description, reference being had to the accompanying drawings, forming part of this specification.

This invention relates to an attachment for banjos, guitars, or similar instruments to provide a bell accompaniment; and the invention consists in features of novelty hereinafter fully described, and pointed out in the claims.

Figure I is a bottom view of the bell attachment secured to the head, with detail of the neck of a banjo or guitar. Fig. II is a horizontal section taken on the staggered line II-III, Fig. IV, and shows the trip-hammer and trigger-trip in their normal position. Fig. III is a like view taken on the same line, and shows the trip-hammer drawn back by the dog-trigger preparatory to striking. Fig. IV is a side view of the head, with a detail of the neck of a banjo or guitar to which the bell attachment is secured, showing the operative parts in their normal position before the pressure of the trip-trigger. Fig. V is an end view of the head of the instrument with its bell attachment in section, and shows the spring-plate that carries the hammer and the trip-dog that operates said plate; and Fig. VI is a vertical section taken on line VI VI, Fig. III, and shows the action of the trip-dog as it releases the spring-plate which carries the hammer.

Referring to the drawings, 1 represents the neck or hand-bar of a banjo, guitar, or other musical instrument; 2, the head that surrounds or constitutes the outer terminal of the same, and 3 are the tension-string pegs, which are inserted and work in the journal-seats 4 in said head.

5 represents the attachment-plate, which is secured to said head by the screws 6, and which attachment-plate carries the following numerous parts: The bell 7; the pedestal 8, 50 that supports said bell, which pedestal is se-

cured to the attachment-plate by the screws 9; the hammer 10; the spring-plate 11, from which said hammer projects, and with which it is integral; the recoil bow-spring 12, that actuates said hammer to strike the bell, the 55 looped-fast end of which spring is secured to said attachment-plate by the screw 13; the bracket 14, secured to said attachment-plate by the screw 15, there being provided a slot-way 16 between said bracket and said attachment-plate, in which slotway said spring 10 works; the pendent spring-boxing 17, which also is secured to said attachment-plate, and within which spring-boxing works the sliding gate; T-head 18, with its spring-bearerstem 19, that carries the spiral spring 20, and the rear terminal of which stem works in the perforate slide-bearing 21 in the rear end of the spring-boxing; the actuating-rod 22, that works said T-spring bearer; the 70 trigger 23, its crank-shaft 24, the crank of which works in the rear terminal loop 25 of the actuating-rod 22, and the journals of which crank-shaft have bearings 26 in the lugs 27, that project from said attachment-plate, and 75 the branch trip-rod 28, which forks from the actuating-rod 22 and carries at its forward terminal the trip-dog 29, that works in the slot 30 in the spring-plate 11, the recessed notch or clutch 31 in which dog embraces said 80 spring-plate to actuate the same when it is desired to ring the bell. These above-mentioned parts, all and several indicated after the mention of the attachment-plate 5, are carried by said attachment-plate, and are with 85 it attachable to the head or neck bar of any banjo, guitar, or other musical instrument, or to other convenient part thereof, by the insertion of the screws 6. A bevel-edge slide 32 on the rear of the trip-dog 29 rides on the bevel-trackway 33, provided on the forward end of the spring-housing, and thus lifts the trip-dog 90 from its embrace of the spring-plate that carries the hammer, when, by the action of the trigger, the hammer has been retired to a 95 point at which it has attained sufficient spring impulse to strike the bell with abundant force after its release.

34 represent a forward bevel-edge on the nose of the trip-dog, which, when the hammer 100

approaches its strike, again lifts the dog 29 in the slot 30 until the notch registers with the spring-plate, on which it then drops and holds it captive until the trip-trigger is again worked. The terminal screw 35 on the end of the pedestal 8 seats the bell through the perforation 36, in the center of which said screw is passed, and said bell is there held by the disk hand-screw 37. We have represented 10 the bell attachment as secured to the head at the terminal of the neck of a banjo, guitar, or other such like musical instrument, being nestled in among the string-adjusting pegs, as when used on that class of string-instruments that is the most convenient position for working the trigger to ring the bell by the hand which is not playing with the strings; but the attachment may be placed in any other suitable position on the instrument that 15 20 25 30 35 40 45 50 55 60 65

the musician may desire, or on any other class of musical instruments to which it would make a pleasing accompaniment.

The operation of the device is as follows: The thumb of the hand that is not occupied 25 playing the instrument to which this attachment is the accompaniment rests lightly on the trip-trigger 23, and in response and accord with the tune that is being played on the instrument a slight pressure of the thumb 30 on said trip-trigger through its crank-connection simultaneously draws both the rod 22, that actuates the sliding gate-head 18 and contracts the spiral spring on its stem-bearer, and at the same time, by means of the trip-rod 28 35 and the trip-dog 29, the spring-plate 11, and the hammer, integral therewith, is drawn back, the bow-spring 12 being also thereby contracted, as well as the spiral spring 20, until the bevel-edge 32 at the rear end of the dog has, with said 40 dog, been lifted by the inclined trackway 33 on the end of the spring-housing, so as to release the clutch-hold of said dog on said spring-plate 11 and the bell-hammer it carries, whereon the united action of the spiral and 45 bow spring quickly projects the hammer forward to ring the bell, and at the same time the bevel-nose 34 of the dog, sliding forward on the inner edge of the slot 30 in the spring-plate 11, again lifts the dog until the recessed 50 clutch registers with said spring hammer-plate and engages therewith, ready for the renewed action of the trigger, which by the said action of the springs has been again projected, the light pressure of the thumb 55 thereon having been in a measure relaxed by the musician in responsive and simultaneous action with that of the springs and the hammer that they project. Although the thumb in the reactionary movement relaxes its pressure on the trigger, as stated, yet it is in continuous contact therewith, and it is almost without an effort on the part of the musician that the action of the one hand becomes responsive to that of the other, or in simultaneous 60 65

accord therewith, and rings up the

accompaniment. With the musician who loves his art, as all true musicians do, it is easier far for both hands to act in unison and in harmony together.

While this bell accompaniment is pleasing 70 in conjunction with all classes of musical instruments, it is especially so with stringed instruments, with which the sonorous and yet clear metallic sounds of the bell seem to provide all that is lacking to effect a perfect harmony amid the softer intonations of the stringed instruments they accompany. 75

We have shown a certain system of springs for actuating the bell-hammer and trigger trip-dog for starting the same; but we do 80 not confine ourselves to that especial construction of the actuating system, for when attached to some classes of musical instruments a change in the construction and disposition of the springs and in the means of 85 tripping the same may be advantageously adopted without departing from the essential features of the invention.

The attachment, besides the musical accompaniment that it provides, also improves 90 the appearance of the instrument.

The bell, being played by the thumb only of the left-hand, does not interfere in any way with the work of the fingers on the strings and finger-board. 95

We claim as our invention—

1. The combination of the attachment-plate 5, the pedestal 8, the bell 7, seated on said pedestal, the trigger-trip, and the spring-actuated hammer that rings the bell, substantially as described, and for the purpose set forth. 100

2. The combination of the attachment-plate, the pedestal, the bell seated on said pedestal, the bow-spring 12, the spring-plate 11 at the 105 loose terminal of said spring, the bell-hammer integral with and carried by said plate, the said plate being provided with a slot 30, the crank trip-trigger 23, the actuating-rod 22, the branch trip-rod 28, and the trip-dog 29, 110 that is seated in the slot 30 of the spring-hammer plate 11, and whose recessed notch 31 clutches said plate when the hammer is drawn back by the trip-trigger preparatory to its spring propulsion against the bell, substantially as described, and for the purpose set forth. 115

3. The combination of the attachment-plate, the pedestal secured to said plate, the bell seated on said pedestal, the bow-spring 12, the 120 spring-plate at the loose terminal of said bow-spring, the said plate being provided with an open slot 30, the spring-boxing 17, the T-head sliding gate 18, the spring-bearer stem integral with said gate, the spiral spring 20, carried on said stem, the crank trip-trigger, the actuating-rod 22, that connects from said trip-trigger with said T-head sliding gate to operate the same, the branch trip-rod 28, integral with said rod 22, the trip-dog 29 at 125 130

the forward terminal of the rod 22, which dog works in the slot 30 of the spring-plate 11, and its recess-clutch 31 when operative engages said spring-plate, the rear and forward bevel-edges 32 and 34 of the trip-dog, and the inclined track on the forward end of the spring-housing, up which the bevel-edge 32 of the trip-dog rides to effect the trigger-trip of the spring-hammer, substantially as and for the purpose set forth.
